BY Shie & Shie ATTYS.

UNITED STATES PATENT OFFICE.

ALTON E. GOSSO, OF CHICAGO, ILLINOIS.

COT.

1,089,545.

Specification of Letters Patent. Patented Mar. 10, 1914.

Application filed September 12, 1912. Serial No. 719,941.

To all whom it may concern:

Be it known that I, ALTON E. Goso, a citizen of the United States, residing at 164 North Central avenue, Austin Station, Chicago, in the county of Cook and State of Illinois, have invented certain new and useful Improvements in Cots, of which the following is a description.

My invention belongs to that general class 10 of devices known as cots or beds, and relates particularly to a suitable cot and resilient adjustable supporting means therefor, for use wherever found applicable.

The present invention is somewhat in the 15 nature of an improvement over the adjustable folding spring cot shown in my pending application, Serial No. 654,347, filed October 12, 1911, the same being more convenient and satisfactory for some of the 20 uses set forth in that application.

The present device is particularly adapted 25 for use on common carriers, such as railway trains, boats and the like, and on ambulances, police patrols, and similar places, for caring for the sick and injured. It is also 30 particularly adapted for military uses, either on the field or for emergency hospitals, or on trains or boats transporting troops. By the employment of one or a 35 number of the devices, ordinary box cars, baggage cars, boats, warehouses, or any other place suitable for a shelter, may be readily and comfortably converted into a suitable habitation for housing any number 40 of persons, either in an emergency or for a considerable length of time. Any common carrier may be easily equipped, so that whenever occasion requires, as for instance on excursions, more bunks or berths, they 45 may be quickly provided and placed in position. Owing to the particularly convenient form of supports, the occupant of the cot is not only comfortably supported, but a considerable number of persons may, in an emergency, be gathered in small space.

To this end my invention consists in the novel construction, arrangement and combination of parts herein shown and described, and more particularly pointed out 50 in the claims.

In the drawings wherein like reference characters indicate like or corresponding parts—Figure 1 is substantially a perspective and vertical sectional view of my de- 55 vice applied to a railway car. Fig. 2 is an

enlarged view of the upper portion of one of the supporting members. Fig. 3 is a similar view of the lower portion of the same. Fig. 4 is a perspective view of the bed or stretcher part; and Fig. 5 is a cross sectional view of one of the side bars.

Referring to the drawings, the stretcher or bed part consists of a pair of side bars 1, 1, of any suitable material, as shown, tubular metal bars. Arranged upon and carried by 65 the bars is a carrier 2 of canvas or other suitable material, the same being turned back as at 3 (see Fig. 5) and sewed or otherwise secured so that in folding the side bars 1, 1 may be withdrawn if desired. 70 When in use the side bars 1, 1 are spaced and maintained in the proper relation to each other by a spacer bar 4 arranged at each end and suitably secured to the side bars. As shown, the spacer bars 4 are each 75 provided with a ring-shaped member 5 at each end of a size to slip over the bars 1.

The bed or stretcher part just described is supported by springs 6, there being one arranged at each corner. The springs 6 80 are provided with hooks 7 adapted to engage suitable supports and hooks 8 adapted to carry the bed or stretcher part. Referring particularly to Fig. 5 in which the same is most clearly shown, the bars 1 are 85 provided at each end with holes or openings 9. Extending through each of the holes is a looped wire or equivalent part 10 having an eye 11 for engagement with the hook 8 on the spring 6. The free ends 12 90 of the parts 10 are preferably bent or offset transversely bars 1 or longitudinally the same, as may be desired to engage the bars. As shown they are bent transversely the bars and support the same when the bars 95 are carried by the hooks 8 engaging the eyes 11. The parts 10 are also preferably slightly bent or offset as at 14 so as to engage the sides of the lower hole 9 and prevent the eye members from slipping through 100 the bars and becoming lost when the hooks 8 are disengaged.

Referring to Fig. 1, 15 represents a car roof or equivalent support provided with eyes or hooks 16 and 17 represents a car 105 floor or the equivalent provided with eyes or rings 18 or their equivalent. The cots or stretchers may be supported singly or in tiers, as shown in Fig. 1. As shown there are four hooks 16 and four rings 18 for each 110

cot or tier of cots. Carried by each of the hooks 16 is a chain 19, 20, the two parts being preferably joined by a spring member 21 which serves as a shock absorber and also 5 maintains the chains taut. The chains are connected to the eyes or rings 16 and 18 by hooks 22 and 23 or their equivalents for the purpose. In setting up the beds the hooks 7 on springs 6 may be hooked into 10 any of the links of the supporting chains so as to support the cots at the desired heights from the floor, and by this construction the cots may be inclined or arranged in any desired way, depending upon the use to which 15 they are put.

I have particularly illustrated and described the device applied to a railway car, such as a baggage car, but it may, of course be applied to freight cars, on boats or steamers, or in camps, or wherever desired. Its use is not confined entirely to the handling of sick or injured, or for military purposes, as it is equally applicable and convenient for the housing of laborers or construction 20 gangs, and in this connection I would particularly mention that it is very sanitary and desirable for the accommodation of section gangs employed in railway construction work. When so used it takes the place 25 of the very insanitary permanent bunks, cots or other beds. Vermin or harmful germs may be easily and quickly removed by taking down the devices, washing or otherwise cleaning the canvas carriers, and 30 treating or washing the supports, bars, spreaders, etc. The importance of this cannot be overestimated. When used on conveyances any vibration in transit or owing to stopping or starting is avoided by 35 the use of the shock absorbers 21.

When the device is not desired, it may be unhooked from the floor or ceiling, folded in a compact bundle and stowed away.

Having thus described my invention, it is 40 obvious various immaterial modifications may be made in the same without departing from the spirit of my invention, hence I do not wish to be understood as limiting myself to the exact construction, arrangement or 45 combination of parts herein shown and described, or uses mentioned.

What I claim as new and desire to secure by Letters Patent is:

1. In a device of the kind described and in combination, a plurality of supporting 55 members, a depending chain carried by each part and detachable therefrom, means for yieldingly securing the depending ends of each of said chains, a suitable bed part and means for adjustably, detachably and re- 60 siliently securing said bed part to each of said chains.

2. In a device of the kind described and in combination, a plurality of supporting members, a depending chain carried by each 65 member and detachable therefrom, means for securing the depending ends of each of said chains, a spring for each chain, each spring provided with means for detachably and adjustably engaging the chain, and a 70 bed part detachably carried by said springs.

3. In a device of the kind described and in combination, a plurality of suitable supporting members arranged for attachment to a fixed support, a flexible member secured 75 to said supporting members, means for securing the depending ends of said flexible members to the floor of the structure, and a bed comprising a pair of side bars, a carrier secured thereto and means for resiliently securing said side bars to said flexible members at the desired point between the floor 80 and said flexible member supports.

4. In a device of the kind described and in combination, a plurality of supporting 85 members arranged to be secured to the ceiling of a suitable structure, a chain detachably secured to said supporting members and depending therefrom, a spring arranged proximate the lower end of each of 90 said chains, means for detachably securing said springs to the floor of the structure, and a bed part resiliently secured to said chains and detachable therefrom.

In testimony whereof, I have hereunto 95 signed my name in the presence of two subscribing witnesses.

ALTON E. GOSSO.
